UNITED STATES PATENT OFFICE

PAUL SCHUMACHER, OF MAGDEBURG, GERMANY

APPARATUS FOR DYEING PAPER AND CARDBOARD DURING THE MANUFACTURE ON PAPER MAKING MACHINES

Application filed June 23, 1930, Serial No. 463,295, and in Germany January 20, 1927.

This invention relates to an apparatus, which enables the paper to be provided with colored designs and inscriptions in any desired number of colors during the production of the paper. As apparatus the known 5 Egoutteur cylinder is used, which is provided with metal grooves, pieces of felt or other material adapted to absorb liquid, and which transfers the color to the unfinished 10 still wet papers. In this manner it is possible to provide white and vat dyed papers with designs and inscriptions of any desired colors in a single working operation. This method presents the advantage that the production is much cheaper than by the methods hitherto known, in which only finished 15 papers (mostly wrapping paper comes into question) were provided with multicolor designs, etc. by printing or etching, which 20 could only be effected in several operations.

Hitherto Egoutteur cylinders were used almost exclusively for impressing water marks. It is true however that they have already been used for applying designs and 25 inscriptions to the paper mass, whilst still in moist condition, but these designs and inscriptions were only single colored, as the color had to be conveyed by a cylinder dipping in a vessel over a distributing cylinder 30 to the egoutteur.

According to the invention the colors, owing to the employment of the metal grooves, felt parts and similar dye carriers, to which the color is supplied from inside by color 35 conduits rotating with the egoutteur, are transmitted directly to the paper mass in a single operation. The egoutteur is preferably connected co-axially with a chamber cylinder, which contains the different colors, separated the one from the other. Each 40 chamber must be connected by a separate color conduit with a surface of the material giving up the color.

It is advisable to arrange a nozzle or group 45 of nozzles in front of the Egoutteur cylinder. It is then possible to provide noncolored paper with a ground color or to provide papers, which have already been given a ground 50 color in the vat, with further colors, where-

upon the design or the like is pressed in by the egoutteur.

It should here be mentioned that color cylinders already exist for simultaneously applying different colors to which cylinders 55 the color is supplied from the inner side. The designs, etc. are already cut out of the casing of the cylinder, which consequently acts as a template. The colors, which are stored in different containers, are sprayed 60 by an injector. Spraying is however less advantageous than pressing for obtaining designs with clear contours. Moreover the disadvantage also exists, that for each design a separate casing must be provided, and 65 the ring containing very complicated cams or the like for controlling the valves of the color containers must be exchanged, whereas, according to the invention, merely the metal grooves, felt parts or the like need be 70 changed on the Egoutteur cylinder.

An embodiment of the invention is illustrated by way of example in the accompanying drawings in which

Fig. 1 shows diagrammatically the arrangement of the nozzle and the Egoutteur cylinder on the jiggling part of the paper making machine.

Fig. 2 shows the egoutteur in top plan view.

Fig. 3 is an end view of the egoutteur.

The mass layer runs in known manner along the metal cloth *a*, which is guided over the end rolls *b*. The mass layer is exposed between the register cylinders *c* and the top bands *d*. Behind the roll *g* for reversing the top bands nozzles *h* are arranged, to which the color is supplied by a pipe *k*. These nozzles can be arranged stationary or movable, for example they may describe in known 75 manner gyrating or oscillating movements, and thereby form a pattern of any kind on the surface of the material. The color is supplied from containers through the pipes *k*, which containers are preferably under pressure of compressed air and arranged below or 80 above the paper making machine.

The egoutteur *i* according to the invention is illustrated in Figs. 2 and 3 of the accompanying drawings. The egoutteur is pro- 95 100

vided with surface recesses *r* instead of the metal wires forming the water marks, which recesses are formed either as small metal grooves or of hard felt. In both instances the surfaces fill with color, which is supplied to the cylinders on the rotation of the egoutteur.

The feed of the color is effected in the following manner:

- 10 At the side of the Egoutteur cylinder *i* and coaxially therewith a chamber cylinder *m* is arranged, which is divided into a plurality of compartments by partitions *o*, which compartments are filled with different colors. A conduit *n* leads from each compartment to a color carrying surface *r*. In this manner several colors may be applied at the same time, if to each felt piece or the like a different color is supplied and it is seen that the felt pieces do not come into contact with each other. The feed of the color from the divided drum *m* to the color surfaces *r* is effected by compressed air, which is supplied to the individual compartments through the conduit *p*. In this manner any desired number of colors may be held available. The compartments not required are closed. The divided drum *m* must naturally rotate same as the egoutteur.

30 I claim:

1. An apparatus for coloring paper and cardboard during manufacture on the paper making machine, comprising in combination an Egoutteur cylinder adapted to press the color into the paper mass whilst still in moist condition, and metal grooves on the circumference of said cylinder corresponding to the design adapted to take up liquid color.

- 40 2. An apparatus for coloring paper and cardboard during manufacture on the paper making machine, comprising in combination an Egoutteur cylinder adapted to press the color into the paper mass whilst still in moist condition, and felt pieces on the circumference of said cylinder corresponding to the design adapted to take up liquid color.

- 50 3. An apparatus for coloring paper and cardboard during manufacture on the paper making machine, comprising in combination an Egoutteur cylinder, color absorbing means corresponding to the pattern of the design arranged on the circumference of said egoutteur, a chamber cylinder arranged coaxially with said Egoutteur cylinder, and a conduit connecting each of said chambers to one of said color absorbing means, each of said chambers being under pressure.

- 60 4. An apparatus for coloring paper and cardboard during manufacture on the paper making machine, comprising in combination an Egoutteur cylinder, color absorbing means corresponding to the pattern of the design arranged on the circumference of said egoutteur, a chamber cylinder arranged coaxially

with said Egoutteur cylinder, a conduit connecting each of said chambers to one of said color absorbing means, and a nozzle arranged in front of said Egoutteur cylinder.

5. An apparatus for coloring paper and cardboard during manufacture on the paper making machine, comprising in combination an Egoutteur cylinder, color absorbing means corresponding to the pattern of the design arranged on the circumference of said egoutteur, a chamber cylinder arranged coaxially with said Egoutteur cylinder, a conduit connecting each of said chambers to one of said color absorbing means, and a group of nozzles arranged in front of said Egoutteur cylinder.

In testimony whereof I affix my signature.
PAUL SCHUMACHER.
